UNITED STATES PATENT OFFICE.

EDWARD C. ALLEN, OF NEW HAVEN, CONNECTICUT.

MEANS FOR STOPPING RAILWAY-TRAINS AT DANGER-SIGNALS.

1,386,302.

Specification of Letters Patent.

Patented Aug. 2, 1921.

Application filed September 15, 1920. Serial No. 410,428.

To all whom it may concern:

Be it known that I, EDWARD C. ALLEN, a citizen of the United States, residing at New Haven, in the county of New Haven 5 and State of Connecticut, have invented a new and useful Improvement in Means for Stopping Railway-Trains at Danger-Signals; and I do hereby declare the following, when taken in connection with the accompanying drawings and the characters of reference marked thereon, to be a full, clear, and exact description of the same, and which said drawings constitute part of this application, and represent, in—

15 Fig. 1, a side view partly in section and partly diagrammatic, illustrating the application of my invention to a locomotive.

Fig. 2, a top or plan view of the valve actuating mechanism.

20 Fig. 3, a perspective view of the cam block detached.

Fig. 4, a perspective view of one form of abutment and tripper adapted to be used in connection with my device.

25 Fig. 5, an end view of a sliding abutment in connection with a common form of railway signals.

Fig. 6, a plan view of the same.

Fig. 7, a plan view of the throttle lever 30 release mechanism on an enlarged scale.

This invention relates to an improvement in means for stopping railway trains at danger signals and particularly to that class which includes mechanism operated by an 35 abutment at one side of the tracks and which act to close the throttle lever in the engine and open the train line to the air-brakes, the object of the invention being a simple arrangement of parts which will positively 40 act in case the train passes a stop signal and which will act at desired points if the engine is exceeding a pre-determined speed limit and the invention consists in the construction and arrangement of parts as will 45 be hereinafter pointed out and particularly recited in the claims.

In carrying out my invention, I employ a lever 10 having an abutment arm 11 and a tripping arm 12 for such purposes as will 50 hereinafter appear. This lever is connected with a cam block 13 supported in a suitable housing upon a stud 14, this cam having a flat face 15 normally bearing against a disk 16 on the end of a stem 17, the disk 16 being 55 normally held against the cam block by a spring 18. In line with the stem 17 is a

valve stem 19 operating a valve 20 to open connection between an auxiliary train line pipe 21 from the engineer's brake valve 47 controlling the main train line 48 to an exhaust pipe 22 leading to a cylinder 23 having a piston 24 the stem 25 of which extends into engagement with a tripping dog 26 connected with the throttle lever 27 so as to trip the latch 28 thereof through the release handle 55 and link 56 (see Fig. 7). The stem 19 is formed with a notch 29 to receive a spring pin 30 by which the valve 20 is locked in its open position, the valve being held in its closed position by springs 31 and 32. 60 The lever 10 extends into a housing 33 through a slot 34 slightly longer than the width of the lever so that the lever may have a slight movement independent of the housing, to prevent the operation of cam 65 block 13 on backward movement of the engine, the lever being held against one end of the slot by a spring 35. For operating the lever 10, I employ an abutment 36 and a tripper 37, the distance between the two 70 being regulated so that the abutment will be engaged by the lever 10 which will turn the lever so that the arm 12 will engage with the tripper to turn the cam block 13 75 sufficiently to operate the valve 20. An 80 actuator as shown in Fig. 1 may be placed in suitable relation to dangerous curves or cross-overs, the height of the abutment and the distance of the tripper being determined by the speed at which the engine should 85 move at such points so that if traveling at a pre-determined speed or slower the arm 11 will not be moved sufficiently to throw the arm 12 into engagement with the tripper 37 or the distance between the abutment and 90 tripper will be such that the lever will have time to recover its normal position before it reaches the tripper. On the other hand, if the engine is traveling at a speed higher than with safety the arm 12 after being 95 depressed by the engagement of the arm 11 with the abutment 36 will engage with the tripper 37 and so turn the cam block 13 to operate the valve 20, thus allowing pressure of the main train line to enter the cylinder 23 and automatically throw the throttle lever and at the same time open the train line of the air-brakes and when the valve 20 is open, the spring-pin 30 engages 100 the notch 29 and holds it in its open position until it has been manually released. It 105 will be understood that the cylinder 23 will 110

be provided with an exhaust 38, so that after the valve 24 in the cylinder has moved forward the operative fluid may escape, and it may here be stated that the connections 5 through the exhaust pipe 22 may be comparatively loose, or cylinder 23 provided with a leakage groove so that any pressure therein will escape. If the trains are controlled by the usual block signals, I preferably employ an abutment 39 having sections 40 and 41 of different heights. These abutments will be mounted on a slide 42 controlled by a crank lever 43 connected with a regular signal system including a semaphore arm 44. When the arm is down or the green light showing the slide 42 is re-tired into a suitable housing 45, but if partly raised or showing an orange light the section 40 of the abutment will be projected outwardly into the path of the arm 11 so as to be engaged thereby, and if the engine is traveling at a safe speed the arm 11 will strike the abutment and at once recover before the arm 12 can engage with the tripper 37 and so that the arm 12 will clear the tripper 37, but if the engine is traveling at a speed greater than safety the arm 12 will engage the tripper 37 and operate the air-brakes. If the signal is set for danger or showing a red light, the section 41 of the abutment will stand in the path of the arm 11 and is so high that the arm 12 must necessarily engage the tripper 37 and so stop the train. The lever 10 is also provided with a rearwardly extending arm 49 which will engage the abutment 36 if the engine is traveling backward and in this case the lever 10 will have a slight movement in the housing which will permit the engine to pass the abutment without operating the valve 20. The rearwardly extending arm 49 has a further function of turning the lever 10 to an operative position provided the springs fail and so that the arm 11 may stand in proper position to engage with the abutment 36 and to accomplish this I mount a preliminary abutment 50 suitably in advance of the abutment 36 and with which the arm 49 will engage so as to turn the arm 11 into its operating position. To provide for cutting out the safety device from engines following the leader as with double-headers, I arrange two valves 51 and 52 in the main train line pipe 48 between which the pipe 21 enters. Engines following the leader close both valves so that action of the safety device will have no effect on the main train line the pressure being maintained by a head engine. In the head engine both valves will be open and should an engineer attempt to make the safety device inoperative by closing the valve 51 or 52, he necessarily shuts off pressure in the main train line and as there is more or less leakage in that train line, which is ordinarily fully charged, this leakage will,

in a very short time cause the brakes to creep on and stop the train. The upper end of the flat face 15 of the cam-block, when in its normal position, is cut away or formed with a bevel 53 as shown in Fig. 70 3 of the drawings so that in backing up the cam-block may have a certain amount of free movement before moving the disk 16 sufficiently to open the train line.

By employing the cam block as shown and described, the lever 10 may make a complete revolution if forced to do so by the engagement of the arm 12 with the tripper 37 and hence there is no danger of the parts being broken by the impact of the arms with the 75 abutment or tripper. The action of the device is positive and the train once having been stopped can not proceed until the spring pin has been removed from the valve-stem and allow it to move to a closed position. The engineer cannot prevent the device from operating for the reason that if he should wedge his throttle-valve lever, the escape of air from the pipe 22 and its connection with the cylinder 23 and the exhaust 90 38 in the cylinder will be sufficient to open the main train line to the brakes so then they will thereby be applied. While I have shown and described my invention as applied to a steam-locomotive, it is obvious 95 without further illustrating that it may be applied to an electrically operated motor, the means shown and described for operating the throttle valve being readily adapted to operate the controller lever on an 100 electric motor.

I claim:

1. Means for stopping railway trains at danger signals including a cam block adapted to open the train line, a lever connected with said block and including an abutment arm and a tripper arm combined with an abutment and a tripper for actuating said arms.

2. Means for stopping railway trains at danger signals comprising a cam block having a flat face, an actuating stem adapted to be moved by said cam block, a valve having a valve stem in line with said actuating stem, said valve adapted to open the train line, a cylinder having a piston formed with an outwardly projecting stem and adapted to trip the throttle lever when the said valve is open, a lever connected with said cam block and formed with an abutment arm and a tripping arm and an abutment and a tripper for actuating said arms.

3. Means for stopping railway trains at danger signals including the air-brake system, a valve adapted to open said system, a cam block adapted to be turned to open said valve, a lever connected with said block said lever provided with an abutment arm and a tripping arm and a transversely movable abutment slide controlled by signal 130

mechanism and provided with abutments of varying height adapted to be moved into the path of said abutment arm.

4. Means for stopping railway trains at danger signals including a cam block adapted to open the train line, a stem between said block and valve formed with a notch, a spring-pin adapted to enter said notch when the stem is moved rearward and means connected with said block and adapted to be operated by an abutment for turning said cam block.

5. Means for stopping railway trains at danger signals including the air-brake system and controlling lever, two manually operated valves arranged in the main

train line of the brake system, an auxiliary train line intersecting the main train line between the said valves, and exhaust pipe, a valve between the said auxiliary 20 train line and exhaust pipe, means operated by the exhaust for moving said controlling lever, and means for opening said valve including an abutment arm and means for turning said arm.

In testimony whereof, I have signed this specification in the presence of two subscribing witnesses.

EDWARD C. ALLEN.
